REFRIGERATING APPARATUS

Charles F. Henney, Dayton, Ohio, assignor, by
mesne assignments, to General Motors Cor-
poration, a corporation of Delaware

Application April 25, 1931, Serial No. 532,871

7 Claims. (Cl. 62—99)

This invention relates to refrigerating apparatus and more particularly to an improved refrigerating element for a commercial refrigerator cabinet.

5 In the present types of commercial refrigerator display cabinets for the storage and display of meats and other foods there are a number of objectionable features. In all of the present types the cooling units are difficult and in most cases 10 almost impossible to wash and keep clean and sanitary. There are two general types of cooling means in general use, one type in which the cooling units extend horizontally beneath at least some or all of the shelves, and the other type in 15 which the cooling units, usually of the ordinary multiple finned type, are placed at either end of the cabinet.

In the first mentioned type, it is necessary to place drip pans beneath the cooling units and 20 beneath these drip pans it is necessary to place sweat pans which are insulated from the drip pans and collect the sweat from the drip pan during defrosting. These drip pans are unsightly, unsanitary, inconvenient, and obstruct the 25 vision in viewing the articles displayed within the cabinet. These drip pans collect the drip and if not very frequently washed a scum or fungus growth will form on the drip in the drip pan. Often some of the food or a piece of meat 30 will fall into the drip pan and be rendered unfit for eating. In this type of cooling means the cooling unit is ordinarily unsightly, takes space above and below the shelves, and also decreases the visibility of the articles displayed upon the 35 shelves.

In the second mentioned type the drip pans adjacent the shelves and the attending difficulties thereof are avoided, but other difficulties present themselves. In this arrangement the 40 cooling units take up valuable space at the end of the cabinet. Furthermore the temperature in different parts of the cabinet and on various shelves varies between undesirably wide limits. Relatively rapid convection currents are also set 45 up which withdraw moisture from the meat or other food upon the shelves. These convection currents are set up by the cooling units which must be kept at a temperature considerably below the temperature of the air confined within 50 the cabinets to maintain a sufficient rate of convection to satisfy the minimum cooling requirements in the parts of the cabinet remote from the cooling units. This relatively high temperature differential tends to reduce the overall efficiency of the refrigeration and in addition the

moisture in the air collects as frost upon the cooling unit and lowers the efficiency thereof.

Accordingly one of the objects of the invention is to provide an improved cooling unit for a commercial refrigerator cabinet having a large 5 amount of surface area to reduce the amount of moisture withdrawn from the food stored within the cabinet and having an improved type of cooling element positioned in such a relation with the cabinet and the shelves so as to localize circulation. 10

Another object of the invention is to provide a cooling unit having an attractive appearance, increased visibility, and constructed so as to take up a minimum amount of useful cabinet space. 15

A further object of the invention is to provide an improved cooling unit which can be easily washed and kept clean, and to be as sanitary as possible.

Further objects and advantages of the present 20 invention will be apparent from the following description, reference being had to the accompanying drawing, wherein a preferred form of the present invention is clearly shown.

In the drawing:

Fig. 1 is a sectional view along the line 1—1 of Fig. 2 of a commercial refrigerator display cabinet disclosing an embodiment of the improved cooling unit together with a diagrammatic illustration of the remaining elements of a compression refrigerating system; 25

Fig. 2 is a transverse sectional view along the line 2—2 of Fig. 1;

Fig. 3 is a sectional view along the line 3—3 of Fig. 4 showing a slightly modified form of the 35 cooling unit embodying the invention;

Fig. 4 is a sectional view along the line 4—4 of Fig. 3;

Fig. 5 is a sectional view of a modified form of plate type cooling element for the cooling unit 40 shown in Fig. 1, and

Fig. 6 is a fragmentary side view of the modified form of plate type cooling element shown in Fig. 5.

In Fig. 1 for illustrative purposes there is shown 45 diagrammatically a compression refrigerating system including a compressor 21 for compressing a refrigerant and for forwarding it through the conduit 22 to the condenser 23 where the refrigerant is liquefied and is collected in the receiver 24. The liquefied refrigerant collected in the receiver 24 is forwarded through the conduit 25 to the float chamber 26 of the cooling unit 27 situated within the commercial refrigerator display cabinet 28. This cabinet or case 28 is of 50

the ordinary sloping front type having a window 34 at the front and a plurality of doors 35 and 36 at the rear. The liquid refrigerant supplied to the float chamber 26 vaporizes in the 5 cooling unit 27 because of the heat absorbed from the interior of the cabinet 28 and this vaporized refrigerant is returned from the float chamber 26 through the conduit 29 to the compressor 21. An electric motor 30 is connected 10 by pulley and belt means 31 to the compressor for driving the compressor 21. A pressure responsive switch means 32 is preferably connected to the return conduit 29 to provide intermittent operating and idle periods of the compressor according to the pressure and consequently the 15 temperature of the cooling unit 27. The float chamber 26 contains a float ball 33 for regulating the supply of liquid refrigerant coming from the supply conduit 25 so as to maintain a certain 20 level of refrigerant within the float chamber 26. Because of the partial solubility of the lubricant for the compressor in the liquid refrigerant and because the liquid refrigerant is heavier than the lubricant, a blanket of lubricant 34 floats upon 25 the liquid refrigerant in the float chamber 26.

The main cooling portion of the cooling unit consists of a plurality of plate type cooling elements 37, 38 and 39. Each of these cooling elements have a header at their upper and lower 30 ends which are connected by a plurality of refrigerant ducts situated in a single plane. The upper headers of the plate type cooling elements 37, 38 and 39 are designated by reference characters 40, 41 and 42 and the lower headers are 35 designated by 43, 44 and 45. In each of the plate type cooling elements a sheet metal plate is soldered or bonded to the refrigerant ducts connecting the upper and lower headers, making a unitary plate type cooling element having a 40 large conducting surface. The plate type cooling elements 37, 38 and 39 are supported in a vertical position and transversely of the cabinets 28 by brackets 46, 47 and 48 which are fastened to the top of the cabinet 28. These plate type cooling 45 elements 37, 38 and 39 therefore divide the cabinet 28 into four main cooling chambers or zones 49, 50, 51 and 52.

In the embodiment shown in Fig. 1, shelves 53 and 54 are supported between the cooling elements 37 and 38 by brackets 55 which are fastened in proper positions to the cooling elements 37 and 38. Similar shelves and brackets are provided between the cooling elements 38 and 39 and also between the cooling element 37 and the 55 adjacent end of the cabinet 28. It will thus be seen that the ordinary shelf supports are eliminated and the thin plate-type cooling elements take the place thereof. Thus the space ordinarily occupied by the cooling unit is released 60 for display purposes. A liquid conduit 60 extends downwardly from the bottom of the float chamber 26 and connects to the lower header 45 for supplying liquid refrigerant to the cooling element 39. A second liquid conduit 61 conducts 65 liquid refrigerant from the lower header 45 of the cooling element 39 to the lower header 44 for supplying refrigerant to the cooling element 38. A third liquid conduit 62 conducts liquid refrigerant from the header 44 to the lower header 43 70 for supplying the cooling element 38 with liquid refrigerant. A plurality of upper connecting conduits 63 conduct vaporized refrigerant from the upper header 40 of the cooling element 37 to the upper header 41 of the cooling element 38 75 while a plurality of upper connecting conduits

64 conduct vaporized refrigerant from the upper header 41 of the cooling element 38 to the upper header 42 of the cooling element 39. The upper header 42 of the cooling element 39 is connected by a plurality of couplings 65 to the float chamber 26, preferably above the level of liquid refrigerant and preferably at the level of the oil blanket 34 in the float chamber. With this construction, the gaseous refrigerant carries some of lubricant in the blanket of lubricant along with it back to the 10 compressor. In this manner, the blanket of lubricant is prevented from becoming excessively thick and heavy. In order to minimize the returning of liquid refrigerant to the float chamber 26 from the cooling elements 37, 38 and 39, 15 fins 66 and 67 are provided upon connecting conduits 63 and 64 as well as the couplings 65. These fins cause a greater amount of heat to be absorbed by these upper connecting conduits so that any liquid refrigerant passing therethrough 20 will vaporize. The float chamber 26 is supported by a bracket 68 fastened to the top of the cabinet 28.

In my improved cooling unit an excellent circulation is maintained. The cold liquid refrigerant passes downwardly from the bottom of the float chamber 26 through the conduit 60 and feeds the lower headers of the cooling elements 37, 38 and 39. The cooling elements absorb heat from the air within the cabinet and from the 30 shelves 53 and 54, causing the liquid refrigerant within the connecting ducts of each cooling or refrigerating element to vaporize and pass upwardly to the upper headers where the vaporized refrigerant separates from the liquid refrigerant 35 and is conducted through the upper connecting conduits back to the float chamber 26 from which point it is returned to the compressor through the return conduit 29.

A novel feature of my improved cooling unit 40 is the provision of the sets of individual drip pans 70 and 71 which are placed directly beneath the connecting conduits 63 and 64 to collect any moisture which might drip therefrom. These individual drip pans are narrow and allow circulation of the air within the cabinet over the connecting conduits. The drip pans 70 and 71 are sloped so as to allow the drip to drop to the bottom of the cabinet at one end of the drip pan close to the edge of the shelf adjacent a cooling 50 element so that the drip will not drop upon any food which may be placed on the shelves. Any moisture which collects upon the plate-type cooling elements will run down the cooling elements and drop to the bottom of the cabinet. The bottom of the cabinet is preferably provided with 55 a collecting basin and drain.

In my improved arrangement the evaporating or withdrawing of moisture from the food stored in the cabinet is minimized because of the large 60 surface area of the plate type cooling elements and because the circulating within the refrigerator cabinet is restricted to a plurality of small cooling zones or chambers. In addition the cooling elements 37, 38 and 39 acting as partitions, 65 the shelves 53 and 54, when food is placed thereon, also act as partitions. By employing small cooling chambers or zones all parts of the cabinet may be properly cooled with little differences in temperature and without rapid convection currents. Consequently the withdrawal of moisture from the meat or other food is minimized and frosting of the different parts of the cooling unit 70 prevented entirely or greatly reduced.

It is evident that the shelves may be removed 75

and with the cooling elements, as well as the interior of the cabinet, be washed with comparative ease.

In the modification shown in Figs. 3 and 4 the cabinet 80 is shown having a cooling unit provided with a plurality of plate type cooling elements 81 similar to the cooling elements shown in Figs. 1 and 2. This cooling unit is provided with a float chamber 82 supported from the top 10 of the cabinet 80. The upper headers 83 of the plate type cooling elements 81 are connected to the float chamber 82 by individual conduits 84 instead of being connected in a parallel series arrangement as in Figs. 1 and 2. The liquid conduit 85 for supplying the cooling elements 81 depends from the float chamber 82 and connects to the lower header of the plate elements 81 in a manner similar to that shown in Figs. 1 and 2. This modification illustrates the flexibility of 20 this type of cooling element. These plate type cooling elements may also be used with a direct expansion refrigerating system.

In Figs. 5 and 6 a plate type cooling element 90 is shown in which the upper and lower headers 91 and 92 as well as the connecting refrigerant ducts 93 are formed of two sheets of metal 94 and 95 which are formed to the proper configuration by a stamping operation and welded together to form the cooling element. This cooling 30 element is preferably coated with porcelain or other suitable finish in order to present an attractive appearance. This cooling element, if desired, may be substituted for the cooling elements 37, 38 and 39 which are shown in Fig. 1 or the cooling elements 81 in Fig. 2.

While the form of embodiment of the invention as herein disclosed constitutes a preferred form, it is to be understood that other forms might be adopted, all coming within the scope of 40 the claims which follow.

What is claimed is as follows:

1. In a commercial refrigerator, an insulated cabinet, a float chamber in the cabinet, a plurality of individual plate type refrigerating elements individually supported by the cabinet in vertical positions and in widely spaced horizontal relation within the cabinet to divide the cabinet into a plurality of distinct cooling chambers, a conduit connecting the lower portion 45 of the float chamber with the lower portion of said plate type refrigerating elements for supplying said elements with liquid refrigerant, and a plurality of conduits connecting the upper portion of said cooling elements with the float chamber for conducting refrigerant from said elements.

2. In a commercial refrigerator, an insulated cabinet, a float chamber in the cabinet, a plurality of plate type refrigerating elements supported vertically in spaced relation within the cabinet to divide the cabinet into a plurality of cooling chambers, a conduit connecting the lower portion of the float chamber with the lower portion of said plate type refrigerating elements for supplying said elements with liquid refrigerant, a plurality of conduits connecting the upper portions of said cooling elements with the float chamber for conducting refrigerant from said elements, and fins on said last mentioned conduits for preventing the return of liquid refrigerant through said float chamber through said conduits.

3. In a commercial refrigerator, an insulated cabinet, a float chamber in the cabinet, a plu-

rality of plate type refrigerating elements supported vertically in horizontal spaced relation within the cabinet to divide the cabinet into a plurality of cooling chambers, a conduit connecting the lower portion of the float chamber with the lower portion of said plate type refrigerating elements for supplying said elements with liquid refrigerant, a plurality of conduits connecting the upper portions of said cooling elements with the float chamber for conducting refrigerant from said elements, and individual drip pans for each of said last mentioned conduits for catching the drip from said conduits.

4. In a commercial refrigerator, an insulated cabinet, a float chamber in the cabinet, a plurality of individual plate type refrigerating elements individually supported by the cabinet in vertical positions and in widely spaced horizontal relation within the cabinet to divide the cabinet into a plurality of distinct cooling chambers, a conduit connecting the lower portion of the float chamber with the lower portions of said plate type refrigerating elements for supplying said elements with liquid refrigerant, and a plurality of individual conduits individually connecting each of the upper portions of said cooling elements with the float chamber for conducting refrigerant from said elements.

5. In a display case refrigerator a cabinet having a compartment to be kept cool, a plurality of individual plate type cooling elements having an impervious wall, said elements being individually supported by the cabinet in a vertical plane, and arranged transversely in widely spaced relation in said compartment to divide said compartment into a plurality of distinct chilling chambers, means for storing food within said chilling chambers between said cooling elements, common means for supplying refrigerant to the lower portions of said plate type cooling elements and for withdrawing refrigerant from the upper portions of said plate type cooling elements.

6. In a display case refrigerator, a cabinet having a compartment to be kept cool, a plurality of individual plate type cooling elements having an impervious wall, said elements being individually supported by the cabinet in vertical positions, and arranged in widely spaced horizontal relation in said compartment to divide said compartment into a plurality of chilling chambers, said cooling elements having a header at their lower end, a header at the upper end and a plurality of connecting refrigerant passages formed therein, and means for supplying refrigerant to the lower header and for withdrawing refrigerant from the upper header of said cooling elements.

7. Refrigerating apparatus including a cabinet having a compartment to be cooled, a plurality of individual plate type cooling elements having impervious walls, said cooling elements being vertically disposed and horizontally spaced in said compartment to divide the compartment into a plurality of distinct chilling chambers, means for storing food within said chilling chambers between said cooling elements, common means for supplying refrigerant to the lower portion of each of said plate type cooling elements and for withdrawing refrigerant from the upper portion of each of said plate type cooling elements.

CHARLES F. HENNEY.
